[57] ABSTRACT

A self-propelled drilling rig for boring blastholes and small-diameter wells is disclosed, said rig comprising a carriage mounted on the frame of an undercarriage and provided with a manipulator carrying a boring tool. The drilling rig is provided with a servomechanism having a hydraulic drive with a reduction gear, which is operatively connected to a longitudinally movable slide valve, and a plate attached to the slide valve and co-operating with a pusher rigidly secured to the jib manipulator.

SELF-PROPELLED DRILLING RINGS FOR BORING BLASTHOLES AND SMALL-DIAMETER WELLS

BACKGROUND OF THE INVENTION

The present invention relates to self-propelled drilling rigs for boring blastholes and small-diameter wells.

Known in the art is a self-propelled drilling rig for boring blastholes and small-diameter wells, said rig comprising a carriage mounted on the frame of an undercarriage and provided with a reciprocatory drive. A jib manipulator is swingably mounted on the carriage, said manipulator being adapted to carry a feeding mechanism for a boring tool. The jib manipulator is displaceable in vertical and horizontal directions by means of a drive mounted on the carriage.

The drilling rig is provided with a servomechanism comprising a hydraulic cylinder mounted on the frame, the movable part of which being connected to the carriage, and the working chambers of the cylinder communicating with the chambers of a slide valve.

The servomechanism is provided with a flexible link, one end of the link being attached to the manipulator and the other end being fixed to the slide valve, and a pulley mounted on the frame and adapted to co-operate with the flexible link (cf. U.S.S.R. Inventor's Certificate No. 215,170).

However, the known drilling rigs cannot cope with growing requirements of higher efficiency and accuracy of the depth of the blastholes being drilled. Furthermore, they have short service life due to rapid wear of the flexible link.

In boring blastholes from lower levels the jib of the manipulator comes into contact with the flexible link and wears it, whereby the servomechanism fails. These frequent interruptions result in time being wasted for repair and replacement of the flexible link.

In order to obtain a predetermined accuracy of the depth of the blastholes being drilled, carriage of a self-propelled rig should move according to the following functional relationship:

$$\Delta l = Z (1 - \cos \alpha \cos \beta),$$

wherein:

Δl is an amount of movement of the carriage relative to the frame of the self-propelled drilling rig;

Z is a length of the manipulator jib;

α is an angle of rotation of the manipulator jib in a vertical plane;

β is an angle of rotation of the manipulator jib in a horizontal plane.

The experience has shown that the kinematic structure of the known drilling rigs cannot ensure the movement of the carriage according to the above-mentioned relationship. As a result, a yield of outsize material of the exploded rock is increased and a rate of advance is decreased.

SUMMARY OF THE INVENTION

It is a main object of the invention to provide a self-propelled drilling rig for boring blastholes and small-diameter wells which has a higher efficiency.

Another object of the invention is to improve the accuracy of the depth of the blasthole being drilled,

whereby uniform crushing of the exploded rock is achieved and the face advance per unit of the length of the blasthole being drilled is increased.

Still another important object of the invention is to increase reliability of the drilling rig in operation.

These and other objects are accomplished by the provision of a self-propelled drilling rig for boring blastholes and small-diameter wells said rig comprising a carriage mounted on the undercarriage frame and provided with a reciprocatory drive and a jib manipulator swingably mounted on the carriage and having a drive adapted to displace a feeding mechanism of a boring tool in vertical and horizontal directions, a servomechanism comprising a hydraulic cylinder mounted on the frame, the movable part of which being connected to the carriage and the working chambers of the cylinder communicating with the chambers of a slide valve of the servomechanism, and a supply source comprising a pump adapted to supply fluid from a tank into said slide valve and conduits for returning the fluid back into the tank, wherein according to the invention the servomechanism is provided with a hydraulic drive with a reduction gear operatively connected to a longitudinally movable slide valve, a plate being attached to said slide valve, which plate co-operates with a pusher rigidly secured to the jib manipulator.

Such self-propelled drilling rig is more reliable in operation and ensures a required accuracy of drilling blastholes at a predetermined depth.

It is expedient that the housing of the slide valve of the servomechanism be operatively connected to the reduction gear, while the stem of the slide valve be spring-loaded, the plate adapted to co-operate with the pusher of the jib manipulator being secured to the stem.

This embodiment of the servomechanism increases its sensitivity.

It is desirable that the stem of the slide valve of the servomechanism be spring-loaded and operatively connected to the reduction gear, while the plate adapted to co-operate with the pusher of the jib manipulator being fixed to the slide valve housing.

This embodiment of the servomechanism ensures low inertia thereof.

The invention will be better understood from the following examples of specific embodiments of a self-propelled drilling rig for boring blastholes and small-diameter wells with reference to the accompanying drawings, in which:

BRIEF DESCRIPTION OF THE DRAWINGS

FIG. 1 shows a side elevation view of the self-propelled drilling rig;

FIG. 2 shows a servomechanism in which the pusher of the jib manipulator co-operates with the plate attached to the slide valve stem;

FIG. 3 shows a servomechanism in which the pusher of the jib manipulator co-operates with the plate attached to the slide valve housing.

DETAILED DESCRIPTION OF THE PREFERRED EMBODIMENT

The self-propelled drilling rig for boring blastholes and small-diameter wells comprises a frame 1 (FIG.1) mounted on an undercarriage 2 of the drilling rig. A

carriage 3 is mounted on the frame 1, and a jib manipulator 4 is swingably mounted on the carriage and is adapted to carry a feeding mechanism 5 for a boring tool 6.

The jib manipulator 4 is displaceable in vertical and horizontal directions by means of drives comprising hydraulic cylinders with slide valves (not shown in the drawings).

The drilling rig is provided with a servomechanism comprising a hydraulic cylinder 7 mounted on the frame 1 (FIG.2), the movable part 8 of the cylinder being connected to the carriage 3, and the working chambers 9 and 10 of the cylinder communicating with a slide valve 11, and a hydraulic drive 12 with a reduction gear 13 operatively connected to the longitudinally movable slide valve 11.

The housing of the slide valve 11 of the servomechanism is operatively connected to the reduction gear 13, while a stem 14 of the slide valve 11 is spring-loaded, and a plate 15 is attached thereto, said plate co-operating with a pusher 16 of the jib manipulator 4.

In another embodiment the stem 14 (FIG. 3) of the slide valve 11 of the servomechanism is operatively connected to the reduction gear 13, while the plate 15 is attached to the housing of the slide valve 11, said plate co-operating with the pusher 16 of the jib manipulator 4.

The self-propelled drilling rig is provided with a fluid supply source comprising a pump 17, which supplies fluid (oil) from a tank 18 into the slide valve 11 of the servomechanism, and conduits 19 for returning the fluid back into the tank 18. The conduits 19 are provided with a safety valve 20.

The self-propelled drilling rig operates in the following way.

For successive drilling of blastholes the carriage 3 should be moved along the frame 1 with respect to the face by an amount Δl depending upon an angle of rotation of the jib manipulator 4 in vertical and horizontal directions.

The pump 17 is energized to supply fluid from the tank 18 into the slide valve 11 of the servomechanism. Then, the drive of the jib manipulator 4 is energized to position the manipulator at an angle corresponding to the blasthole coordinate. Accordingly, the pusher 16 (FIG.2) is rotated, whereby the stem 14 of the slide valve 11 is pulled out, and fluid is fed out of the slide valve 11 through the apertures thereof into the chamber 9 of the hydraulic cylinder 7 to move the movable part (rod) 8 together with the carriage 3 with respect to the frame 1.

The fluid expelled from the chamber 10 of the hydraulic cylinder 7 is fed into the hydraulic drive 12 and further into the slide valve 11 and via the conduit 19 into the tank 18. This puts in operation the hydraulic drive 12 which transmits the motion to the reduction gear 13 to move the housing of the slide valve 11 fol-

lowing the stem 14 until the apertures of the slide valve 11 are closed, whereafter the movement of the carriage 3 and the housing of the slide valve 11 is stopped.

During the rotation of the pusher 16 into horizontal position, the plate 15 together with the stem 14 are retracted into the housing of the slide valve 11, whereby the apertures of the slide valve are open, and fluid from the tank 18 is fed by means of the pump 17 into the hydraulic drive 12 and into the chamber 10 of the hydraulic cylinder 7 to move the rod 8 together with the carriage 3 with respect to the frame 1.

The fluid expelled from the chamber 9 is fed into the slide valve 11 and further via the conduit 19 into the tank 18. At the same time the hydraulic drive 12 is energized to transmit the motion to the reduction gear 13 which moves the housing of the slide valve 11 following the stem 14 until the apertures of the slide valve 11 are closed.

After that the movement of the carriage 3 with respect to the frame 1 and the movement of the slide valve 11 are stopped.

What is claimed is:

1. A self-propelled drilling rig for boring blastholes and small-diameter wells, said drilling rig comprising: a frame mounted on an undercarriage of said drilling rig; a carriage mounted on said frame; a jib manipulator swingably mounted on said carriage for carrying a feeding mechanism of a boring tool; drive means for moving said jib manipulator in vertical and horizontal directions, said drive means comprising hydraulic cylinders with slide valves; and a servomechanism comprising a hydraulic cylinder mounted on said frame, the movable part of said cylinder being connected to said carriage and the working chambers of said cylinder communicating with a longitudinally movable slide valve and with a hydraulic drive provided with a reduction gear operatively connected to said longitudinally movable slide valve, and a plate being attached to said slide valve, said plate co-operating with a pusher rigidly secured to said jib manipulator.

2. A self-propelled drilling rig as claimed in claim 1, wherein the housing of said slide valve of said servomechanism is operatively connected to said reduction gear, while a stem of said slide valve is spring-loaded, and plate cooperating with said pusher of said jib manipulator is attached to said stem.

3. A self-propelled drilling rig as claimed in claim 1, wherein a stem of said slide valve of said servomechanism is operatively connected to said reduction gear, while a plate cooperating with said pusher of said jib manipulator is attached to the housing of said slide valve.
